UNITED STATES PATENT OFFICE.

GEORGE W. MEYERS, OF CHICAGO, ILLINOIS, ASSIGNOR TO BUILDING EQUIPMENTS MANUFACTURING COMPANY, OF CHICAGO, ILLINOIS, A CORPORATION OF ILLINOIS.

MACHINE FOR OPERATING ON SURFACES.

1,320,778.

Specification of Letters Patent.

Patented Nov. 4, 1919.

Application filed December 26, 1916. Serial No. 138,776.

To all whom it may concern:

Be it known that I, GEORGE W. MEYERS, a citizen of the United States, residing in the city of Chicago, county of Cook, and State 5 of Illinois, have invented certain new and useful Improvements in Machines for Operating on Surfaces, of which the following is a specification.

This invention relates to a machine for 10 operating on surfaces such as floors and refers more particularly to a mechanism for scrubbing, polishing or otherwise cleaning the floor or other surface to be operated upon.

15 Among the objects of the invention are to provide a motor or other power driven machine in which the scrubbing brushes or other cleaning or polishing devices are carried by a revolving ring; to provide means for driving this ring and also utilizing the same power for propelling the vehicle; to provide a construction in which the machine is advanced automatically as the scrubbing or polishing ring is revolved so that all 20 portions of the areas covered by the advancing machine are operated upon; to provide means for supporting the machine so as to permit of adjustably regulating the pressure of the brushes or other operating devices upon the floor or other surfaces to be cleaned; to provide means for adjusting the 25 height of the brush carrying devices from the surface to be operated upon so as to compensate for any wear upon the driving 30 wheels; to provide means for automatically supplying to each of the scrubbing or other cleaning devices, water or other suitable cleaning substance; to provide a construction which will be compact and the parts 35 positively driven in timed relation; and in general to provide a new and improved construction of the character above referred to.

The invention also resides in the novel 40 construction of the ring which carries the scrubbing brushes or other operating devices and in such other features of construction as will more fully hereinafter appear.

In the drawings:

45 Figure 1 is a side elevational view, partly in section.

Fig. 2 is a top plan view of the brush supporting ring.

50 Figs. 3 and 4 are enlarged detail views of the brush holding mechanism.

Describing in detail the particular embodiment of my invention shown in the drawings, 1 designates the frame of the machine, 2 the driving axle and 3 the traction wheels, mounted upon the axle and 60 adapted to drive the machine forward. At its center portion the frame is supported by a caster wheel 4, carried by an arm 5, which is pivoted at 6 and can be raised and lowered by means of an adjustment mechanism 65 7, consisting of a lock nut 8 on the threaded stem 9.

While any suitable source of power could be employed for the driving mechanism in the present construction, I have employed a 70 motor 10 on the shaft 11, to which is connected a beveled gear 12, meshing with beveled gears 13 and 14 on the horizontal shaft 15. The gear 13 acts simply as an idler but the shaft on which it is mounted 75 may be employed for driving any suitable tool or other device if desired. The lower end of the shaft 11 is employed for driving the scrubbing ring 16 which, as shown in Fig. 2 has a plurality of arms 17, which at 80 their outer ends support the brush holding devices as follows: Each of the arms 17 has a pair of rollers 18 and 19, which are vertically movable in a slot 20 of the bifurcated lug 21. This bifurcated lug 21 is preferably cast integral with the ring 22. Associated with each of the bifurcated members 21 is a bearing hub 23 and as shown in Fig. 2, there is also intermediate each of these hubs a similar hub 24. Through each 85 of the hubs 23 and 24 there projects a square shank 25, which is vertically adjustable in the hubs but its downward movement is limited by a pin 26. At their lower ends the shanks 25 are each provided with plates 90 27, through which extend screws or other securing members 28 for removably fastening to the shank the brush carrying saddle 29. As shown in Fig. 3, the saddles 29 are each of inverted U-shape and the wooden 100 body portion 30 of the brush 31 is held in position in the saddle by bolts 32.

With this construction the brushes or other operating devices can be easily removed for repair or renewal, and in order 105 to give greater rigidity to the connection, the lower part of the shank 25 is preferably screw threaded at 33 and provided with a lug 34, projecting down into a recess 35 in the body portion 30 of the brush. In order 110

to hold the brushes down into engagement with the flooring or other surface to be operated upon, there is employed a plurality of leaf springs 36, the amount of pressure exerted by these springs being adjustable by tightening or loosening the wing nuts 37.

For revolving the brushes the body portion 16 of the frame carrying the brushes is keyed at 38 to the lower end of the shaft 10 11. Suitable washers or anti-friction devices 39 are arranged above and below the body portion 16 of the brush carrying frame.

As the brushes revolve, water or other cleaning or polishing substance is fed to 15 each of the brushes in the following manner: From a suitable supply tank 40, a conduit 41 leads to the cup 42 formed on the upper surface of the body portion 16. The water fed into this cup through the conduit 20 41 is distributed through channels 43 in the arms 17 to a point of discharge 44, just in advance of the brush.

In order to insure the entire surface 25 passed over by the machine being operated upon, means are provided for automatically propelling the machine forward in predetermined relation to the movement of the ring carrying the scrubbing devices. In detail this driving mechanism comprises a

helical gear 45, which meshes with a gear 46 30 on the stub shaft 47. By means of a sprocket wheel 48, sprocket chain 49 and sprocket wheel 50, the movement of the shaft 47 is transmitted to the main drive shaft 2, and from the latter to the drive wheels 3. 35 The invention is not limited to the particular drive mechanism described, and various other changes in the details of construction and arrangements and combinations of parts can be made within the scope of my invention. 40

I claim as my invention:

1. In a device for operating on floors or the like, the combination with a frame, of arms projecting therefrom, a brush carrying ring, and a connection between the frame arm members and ring including rollers carried by one member and movable in slots in the other member. 45

2. In a device for operating on floors and the like, the combination with a rotatable frame, of arms projecting therefrom, a brush carrying ring, connections between the frame, arm members and ring, said connections including a bifurcated lug member 50 provided with vertical slots and rollers vertically movable therein. 55

GEORGE W. MEYERS.
